UNITED STATES PATENT OFFICE.

AZARIAH Y. PEARL, OF LEBANON, MAINE.

AUGER.

SPECIFICATION forming part of Letters Patent No. 606,575, dated June 28, 1898.

Application filed July 9, 1897. Serial No. 643,988. (No model.)

To all whom it may concern:

Be it known that I, AZARIAH Y. PEARL, a citizen of the United States, residing at West Lebanon, in the county of York and State of Maine, have invented a new and useful Auger, of which the following is a specification.

My invention relates to augers, the same consisting, essentially, in an improvement upon the device shown and described in Letters Patent Nos. 505,844 and 565,500, granted to me, respectively, upon October 3, 1893, and August 11, 1896; and the objects in view are to provide spaced means for supporting the shank or spindle of the bit respectively contiguous to and remote from the bit; to provide a guide-frame of such construction as to fit snugly in the opening formed by the cutting devices, said frame carrying the outer bearing, in which the bit shank or spindle is mounted; to provide means whereby the side cutters may be turned in either direction to avoid the use of a clutch or release, as in the second above-named patent; to provide means for supporting or holding said frame at the desired angle when the operation of boring is commenced; to provide improved means for discharging the cuttings and preventing the same from being carried back into the bore after discharge, and to provide improved means for lubricating and reducing the friction of the operative members of the device.

Further objects and advantages of this invention will appear in the following description, and the novel features thereof will be particularly pointed out in the appended claims.

In the drawings, Figure 1 is a side view perpendicular to the axes of the side cutters of an auger constructed in accordance with my invention, the same being shown in connection with a holder, whereby the guide-frame may be set at the desired angular adjustment. Fig. 2 is a similar view of the auger at right angles to the plane of Fig. 1 or parallel with the axes of the side cutters. Fig. 3 is a vertical section taken in the plane of the axes of the side cutters. Fig. 4 is a side view of the holder detached. Fig. 5 is a plan view of the same. Fig. 6 is a transverse sectional view of the auger on the line 6 6 of Fig. 1. Fig. 7 is a transverse section of the same on the line 7 7 of Fig. 1. Fig. 8 is a section of

the same on the line 8 8 of Fig. 1. Fig. 9 is a detail sectional view of the spider or propeller. Fig. 10 is an inverted plan view of the same. Fig. 11 is an inner side view of one of the clearing-disks. Fig. 12 is an edge view of the same. Figs. 13 and 14 are respectively side and plan views of a stub or follower interchangeable with the bit and adapted for use in boring metal.

Similar numerals of reference indicate corresponding parts in all the figures of the drawings.

1 designates a shank or spindle provided with a longitudinal lubricating duct or channel 2, which is preferably formed axially in the shank or spindle and extending from a point above the cutting-head, where it is provided with an inlet-opening 3, to a point contiguous to the lower end of the shank or spindle, where it communicates with outlet-perforations 4, said shank carrying a suitable bit 5, of which the construction may vary to suit 75 the material which is being bored and the density of such material.

In Figs. 13 and 14 I have shown a stub or follower interchangeable with the bit 5 and adapted particularly for use in boring metal, 80 whereas that shown in Figs. 1 to 3, inclusive, is especially adapted for boring wood. This stub consists of a perforate disk adapted to be threaded upon the lower end of the auger-shank in place of the bit when the tool is to 85 be used in connection with the boring of metal. Obviously the metal is bored in the ordinary way to form a round hole, after which the tool forming the subject-matter of my invention is applied and the stub or follower is 90 inserted in the bore formed by the former-tool, and thereby guides the tool which forms the square opening. The perforations in the disk serve to allow oil and cuttings to pass through in order to lubricate the parts to prevent heating of the stub. The bit is threaded or otherwise detachably secured to the lower end of the shank or spindle and is preferably provided with an upwardly-projecting collar 6, which fits within a sleeve 7, depending from a guide-block 8, and this sleeve is preferably counterbored to provide a seat for a bearing-ring 9 or other equivalent means for reducing the friction.

The depending sleeve 7 by inclosing the 105 upwardly-projecting collar 6 of the bit, said

sleeve extending down approximately to the plane of the upper surface of the bit, prevents cuttings from reaching the thrust-bearing between the lower end of the bit-shank 5 and the bearing-ring 9, and hence prevents the accumulation of obstructions between the coöperating surfaces of the device.

The guide-block is of a construction and function similar to those described in my 10 said former patents, the same being elongated diametrically, as shown in Figs. 7 and 8, and being provided with lateral alined journals 10, upon which are mounted rotary side cutters 11, corresponding in construction 15 with those described in said former patents and held in place by similar means, consisting of screws 12. Rising from the extremities of this guide-block and preferably integral therewith are cross-sectionally angular 20 guide-arms 13, which combine with the guide-block and a connecting-collar 14 at the upper ends of the guide-arms to form a guide-frame, the cross-sectional construction of the guide-arms being clearly shown in Fig. 6, from which 25 it will be obvious that the arms are located diametrically opposite to each other upon a diagonal connecting the remote outer angles of the side cutters, while the spaces on each side between said arms form diametrically 30 opposite outlets through which cuttings are adapted to be discharged laterally, as hereinafter more fully explained.

Alined with the lower bearing 15, which is 35 formed in the guide-block or in the lower end of the frame for the reception of the bit shank or spindle, is an upper bearing, also designed for the reception of the bit shank or spindle, but located at the upper end of the frame remote from the lower bearing in order to 40 positively guide the shank or spindle during the advance movement of the tool. In the construction illustrated this upper bearing is formed in the collar 14, but is preferably enlarged sufficiently to receive a bushing 16, 45 which obviously is replaceable when worn, the bushing being held in place in the collar 14, forming the upper end of the frame, by means of a set-screw 17 or its equivalent. Downward pressure is communicated from 50 the bit shank or spindle to the upper end of the guide-frame by means of a collar 18, secured to the former by means of a set-screw 19 and preferably bearing upon a thrust or bearing ring 20, which is interposed between 55 the lower side of the collar and the upper end of the frame. This bearing-ring is designed to reduce the frictional contact between the parts and may be substituted by any other suitable form of antifriction-bearing. This 60 bushing 16 being of greater diameter than the collar 18 and bearing-ring 20 receives all of the wear at this point due to the rotation of the bit-shank, and being a small part readily detached it is obvious that such bushing may 65 be replaced when worn without incurring any considerable expense, such replacement, however, having the effect of restoring the appa-

ratus to an efficient working condition. It is desirable in devices of this class to provide means whereby the wear of coöperating parts 70 shall not fall upon a part, such as the guide-frame, which can be replaced only at considerable expense and also only by completely dismembering the tool. It is obvious that the bushing may be replaced by simply re- 75 moving the thrust-collar 18.

The guide-frame is of diametrical dimensions equal to the bit, whereby the side surfaces of the guide-arms 13 are in planes tangent to the bit, and the side cutters 11, which 80 are coaxially mounted at opposite sides of the plane of the guide-block, are adapted to cut away the material between the periphery of the bit and the angles formed by the intersection of the perpendicular outer side faces 85 of the guide-arms to form a rectangular opening. This may be clearly understood by reference to Fig. 6, wherein the dotted line *a* represents the circumference of the opening formed by the bit, the parallel dotted lines *b* 90 represent the side surfaces of the guide-block, and the parallel dotted lines *c* the outer sides of the side cutters and which intersect dotted lines *d* to form the angles of the opening produced by the auger. The dotted lines *d* are 95 of a length equal only to the depth or width of the side cutters, and hence between the planes of the inner sides of the side cutters the material is not wholly removed by the bit, a slight web or fin (indicated in Fig. 6 at 100 *e*) being left in place.

In order to suit the cross-sectional construction of the frame accurately to the shape of the opening formed by the auger, I preferably provide the frame between the planes 105 of the inner sides of the side cutters with grooves 21, extending upward upon the arms 13 and having convexed floors corresponding with the peripheral curvature of the bit. (See Figs. 6 and 7.) It is necessary, however, to remove these webs or fins of the material being bored, and hence I employ trimming-disks 22, countersunk in the ends of the guide-block, with their outer surfaces flush with the contiguous surfaces of said guide-block and arms 13, the diameter of each disk being equal to the interval between the inner surfaces of the side cutters. (See Fig. 8.) When boring in metal, these trimming-disks are adapted to be removed, and hence are 110 preferably detachably secured in place by means of journal-screws 23.

In order to maximize the efficiency of the auger, it is necessary to provide means for relieving the cutting members of cuttings as 115 rapidly as they are formed to prevent choking and clogging, and hence in connection with each of the side cutters, which operate in the direction indicated by the arrow in Fig. 1, I provide the contiguous guide-arm 13 with a 120 clearing-finger or deflector 24, formed by extending and undercutting said arm to form a concaved surface concentric with the side cutter and contiguous thereto. This clear-

ing-finger is reduced at its operative end to a sharp edge, which removes cuttings from the side cutter and prevents the same from being carried back into the hole below the 5 cutter and is deflected upwardly at its upper side to allow cuttings to be thrown centrifugally by the side cutters. Furthermore, the space contiguous to the upwardly moving or rising side of each side cutter is open from 10 the plane of the side cutter to the collar 14, hence providing a free outlet for the cuttings. The only outlet for the cuttings carried by 15 the side cutters is between the clearing-finger and the lower end of the other guide-arm.

In the construction illustrated in the drawings the means employed for operating the side cutters consists of a spider or propeller 25, secured to a reduced portion of the bit shank or spindle by means of a sleeve 26 and a set-screw 27 and having a plurality of wings 28, which successively engage the arms of the side cutters and convey rotary motion thereto. In order to facilitate the removal of cuttings 25 from the side cutters, I have found it desirable, furthermore, to concave the front face of each wing of the spider or propeller, as shown clearly in Fig. 10, the term "front face" being used to designate that face which 30 is foremost when the apparatus is operated forwardly under normal conditions and as indicated by the arrow in Fig. 10. On the other hand, the rear face of each wing is preferably convexed, while the lower end is round- 35 ed to avoid unnecessary friction with the arms of the side cutters. (See Figs. 9 and 10.) The wings of the spider or propeller are preferably arranged parallel with the axis thereof, and, being of shorter length, the cut- 40 tings are enabled to pass upwardly beyond the same without unnecessary obstruction, and in order to prevent cuttings from becoming lodged between the guide-block and the rising sides of the side cutters the contiguous 45 portions of the guide-block are cut away to form clearance-channels 29. The concave front faces of the wings also perform the function of preventing the centrifugal discharge of cuttings thereby and serve to hold the cut- 50 tings from being thrown to such points as to cause them to crowd between the ends of the wings and the contiguous surfaces of the guide-arms.

In connection with the above-described 55 mechanism I provide a holder, whereby the guide-frame may be maintained in the desired angular position previous to and during the boring operation. This holder preferably consists of a split collar 30, constructed to fit 60 upon a seat 31, formed by turning down the upper portion of the collar 14. The parallel extremities 32 of the collar are connected by a set-screw 33, which when tightened secures the collar upon the seat 31, the opposite side 65 of the collar being formed with a socket 34 for the reception of the extremity of the holding-rod 35, adapted to rest against an object suit-

able for guiding it to prevent rotation with the bit shank or spindle while not interfering with movement parallel with the axis of said shank or spindle. To provide for the desired angular adjustment of the guide-frame, the collar is preferably fitted with an adjustable graduated ring 36, countersunk or seated in the upper surface of the collar, around the 75 opening therein, and adapted to be locked at the desired adjustment by means of a set-screw 37.

In order that the operation of the holder may be clearly understood, let it be supposed, for example, that the work has been clamped in place and (if of metal) that a round hole of the proper size has been drilled therethrough by means of a tool of any selected or ordinary construction. The auger having an attached 80 stub or follower (shown in Figs. 13 and 14) is then applied, and it is desired to set the frame to agree with the marks on the work, said marks being designed to indicate the position of the angles of the square hole to be 85 drilled. To accomplish this, the shank of the bit is fitted into the spindle of the milling or other machine, the clamp of the holder having been fitted upon the seat 31, with the set-screws 33 and 37 loosened. The handle-bar 90 35 of the holder is then swung around until it bears firmly against the overhanging arm or other fixed part of the machine on that side toward which the auger when revolving will press the handle or bar and tend to keep 95 it in place. In some instances said handle may be clamped to the overhanging arm of the machine. After thus positioning the handle the frame of the bit must be turned 100 manually until by testing with the proper instruments it is in proper alinement with the 105 marks upon the work, after which the set-screw 33 is tightened to clamp the auger-frame firmly to the holder. The operation of the auger can then be instituted without 110 throwing the auger-frame out of alinement. It frequently happens in shopwork that a 115 cutting must be made at an angle from the first cutting, said angle being of a certain number of degrees. The graduated ring, it must be understood, is so fitted in its seat as 120 to be loose even after the set-screw 33 has been tightened to secure the holder upon the seat 31, and when such a second cutting is desired the ring is moved manually until the zero or initial mark thereon is alined with an index-mark shown on the upper edge of the 125 frame, (see Fig. 5,) whereupon the set-screw 37 or an equivalent locking device is tightened. It is obvious that a vernier and glass can be employed in connection with this feature of the tool when absolute accuracy is demanded. Having set the graduated ring in an initial position with reference to the clamp, the set-screw 33 of the frame can be loosened 130 and the frame turned to bring the index-line at the upper end thereof into registration with any desired degree marked on the graduated ring, thereby indicating a certain definite

angle with relation to the initial relative positions of the frame and holder-arm. Hence when the set-screw 33 is tightened and the holder-arm is allowed to again come in contact with the fixed part of the machine the frame will be arranged in a position at the desired angle from its former position to enable the hole to be drilled as required.

From the above description it will be seen that the specific construction of the bit or other cutting parts may be varied to suit the kind and density of the material to be bored without in any way departing from the spirit of my invention, of which an essential feature consists in the provision of spaced and aligned upper and lower bearings for the bit shank or spindle, whereby lateral vibration or deflection is prevented, and of which a further essential feature resides in the provision of guiding devices which correspond approximately in cross-sectional area with the opening formed by the cutting devices of the auger, whereby said guiding devices fit snugly in the opening and positively direct the movement of the tool.

In connection with the above-named advantage with regard to guiding the tool it should be noted, furthermore, that the guide-frame is open-sided to provide for the free discharge of the cuttings, while contiguous to the cutting members the device is provided with means for preventing the cuttings from being carried back into the paths of the cutting members—as, for instance, the deflecting fingers or projections 24, which coöperate, respectively, with the side cutters.

Further advantages of the construction above set forth will be obvious to those skilled in the art, and it will be understood that various changes in the form, proportion, and the minor details of construction may be resorted to without departing from the spirit or sacrificing any of the advantages of this invention.

45 In the construction illustrated in the drawings the guide-frame is arranged to receive the thrust of the shank, whereby it is fed therewith; but in special cases—as, for instance, in connection with machines for car 50 or other heavy work—said frame will be attached directly to a part of the machine and will be advanced therewith and thereby without reference to the shank and without receiving any direct pressure therefrom. For 55 light work the construction illustrated in the drawings is preferable, and as the other arrangement is obvious it is deemed unnecessary to illustrate or more specifically describe the same.

60 Having described my invention, what I claim is—

1. An auger having a shank, cutting-tools operatively connected with for actuation by the shank, to form an angular bore, and a non-rotatable guide-frame having spaced aligned bearings in which the shank is mounted, said frame corresponding in cross-sec-

tional area and contour with the exterior contour or periphery of the cutting-tools, to fit snugly in the bore formed thereby, substantially as specified. 70

2. An auger having a bit-carrying shank, a non-rotatable guide-frame having spaced aligned bearings in which said shank is mounted, and having cut-away sides forming discharge-openings, and side cutters mounted upon said frame and operatively connected with the shank, the upwardly-moving sides of said side cutters being arranged contiguous to the openings in the frame, substantially as specified. 75

3. An auger having a bit-carrying shank, a non-rotatable guide-frame having spaced aligned bearings in which said shank is mounted, and having cut-away sides forming discharge-openings, side cutters mounted upon said frame and operatively connected with the shank, the upwardly-moving sides of said side cutters being arranged contiguous to the openings in the frame, and chip-deflecting fingers or projections on the guide-frame arranged terminally contiguous to the peripheries of the side cutters, substantially as specified. 85

4. An auger having a bit-carrying shank, a guide-frame provided with upper and lower spaced aligned bearings in which the shank is mounted, and also provided with parallel diagonally opposite cross-sectionally angular arms, and side cutters mounted upon the sides 100 of the frame and operatively connected with the shank, downwardly-moving sides of the side cutters being arranged in the paths, respectively, of said cross-sectionally angular arms of the frame, whereby said arms fit in 105 the angles of the bore formed by the auger, substantially as specified. 95

5. An auger having a bit-carrying shank, a guide-frame having upper and lower aligned bearings in which the shank is mounted, said frame comprising a diametrically elongated block arranged contiguous to and above the plane of the bit, parallel guide-arms arranged at the diametrically opposite angles of the block, and a collar connecting the upper extremities of the arms, and side cutters revolvably mounted upon the guide-block, parallel with its side surfaces and flush with the outsides of said arms and operatively connected with the shank, substantially as specified. 110

6. An auger having a rotatable bit-carrying shank, a non-rotatable frame having bearings in which said shank is mounted, and including a guide-block, side cutters mounted upon the guide-block and operatively connected 115 with the shank, and diametrically opposite fin-removing disks mounted upon the frame with their axes perpendicular to the plane of the axes of the side cutters and with their faces flush with the contiguous outer surfaces of the guide-block, substantially as specified. 120

7. An auger having a rotatable bit-carrying shank, a non-rotatable frame having bearings

in which said shank is mounted, and including a guide-block, diametrically opposite side cutters mounted upon the guide-block and operatively connected with the shank, and diametrically opposite fin-removing disks removably mounted upon the frame with their axes perpendicular to the plane of the axes of the side cutters, and with their outer faces flush with the contiguous surfaces of the 5 guide-block, substantially as specified.

8. An auger having a rotatable bit-carrying shank, a frame provided with upper and lower bearings in which said shank is mounted, and including a diametrically elongated 15 guide-block, side cutters mounted upon opposite sides of said guide-block and operatively connected with the shank, the sides of the frame between the planes of the inner surfaces of the side cutters being channeled to 20 form grooves of which the floors correspond in cross-sectional contour with the periphery of the bit carried by the shank, and fin-removing disks countersunk in the ends of the 25 guide-block with their outer faces flush with the contiguous surfaces thereof, substantially as specified.

9. An auger having a rotatable bit-carrying shank, a non-rotatable frame having bearings in which the shank is mounted and arranged 30 to receive the downward thrust of the shank, said frame having at its upper end a collar and at its lower end a guide-block, connected by spaced cross-sectionally angular guide-arms, a collar on the shank to communicate 35 thrust therefrom to said collar, side cutters mounted upon the guide-block, with their outer sides flush with the guide-arms and a spider or propeller for communicating motion from the shank to the side cutters, said spider 40 having a sleeve fitted upon the shank and bearing terminally upon the upper side of the 45 guide-block, substantially as specified.

10. An auger having a rotatable bit-carrying shank, a non-rotatable cross-sectionally 45 angular frame in which the shank is mounted, said shank being provided with upper and lower means for bearing downwardly upon the frame to impart axial thrust thereto, and side cutters mounted upon the frame flush at 50 their outer sides with the surface of the frame and operatively connected with the shank, substantially as specified.

11. An auger having a rotatable bit-carrying shank, a non-rotatable frame having bearings in which the shank is mounted, and which 55 is adapted to receive axial thrust therefrom, said frame being provided at its upper end with a collar having an enlarged bore, a replaceable bushing removably fitted in said 60 bore, a collar removably secured to the shank contiguous, and adapted to communicate pressure to, said bushing, and of less diameter than the same, whereby the said collar of the frame is relieved of pressure, and side cutters mounted upon the frame and operatively 65 connected with the shank, substantially as specified.

12. An auger having a rotatable bit-carrying shank, a non-rotatable guide-block in which the shank is mounted, side cutters 70 mounted upon the guide-block, and a spider or propeller carried by the shank and having radial wings provided with concaved front faces for successively engaging the arms of the side cutters, substantially as specified. 75

13. An auger having a rotatable shank, a bit having an upwardly-projecting collar removably fitted upon the lower end of the shank, a non-rotatable guide-block having a bearing for the shank and receiving downward thrust therefrom, said block being provided with a depending sleeve into which the collar of the bit fits, a bearing-ring interposed between the guide-block and the bit to communicate thrust from the former to the latter 85 and inclosed by said sleeve, and side cutters mounted upon the guide-block and operatively connected with the shank, substantially as specified.

14. An auger having a rotatable bit-carrying shank, a non-rotatable guide-frame having bearings in which the shank is mounted, and carrying side cutters operatively connected with the shank, said frame having at 90 its upper end a bearing portion or seat, and a holder removably fitted upon said bearing portion or seat, and having clamping devices whereby it may be secured to maintain the frame at the desired angular adjustment, and having a graduated ring concentric with the 95 bit-carrying shank, substantially as specified. 100

15. An auger having a rotatable bit-carrying shank, a non-rotatable guide-frame having bearings in which the shank is mounted, and carrying side cutters operatively connected with the shank, said frame having at 105 its upper end a bearing portion or seat, and a holder removably fitted upon said bearing portion or seat and having clamping devices whereby it may be secured to maintain the frame at the desired angular adjustment, a graduated ring mounted for rotary adjustment upon the holder, and means for locking said ring at the desired adjustment with relation to the holder, substantially as specified. 115

16. An auger having a rotatable bit-carrying shank, a non-rotatable frame in which said shank is mounted, and carrying side cutters which are operatively connected with the shank, a holder having a split collar adapted 120 to fit a seat at the upper end of the frame, a set-screw for contracting said collar to clamp the seat of the frame, a graduated ring countersunk in the holder concentric with the bore of the collar, and a locking-screw for the ring, 125 substantially as specified.

In testimony that I claim the foregoing as my own I have hereto affixed my signature in the presence of two witnesses.
